CLAIM

The ornamental design for an audio unit, as shown and described.

DESCRIPTION

FIG. 1 is a top perspective view of the audio unit;

FIG. 2 is a bottom perspective view of the audio unit;

FIG. 3 is a top view of the audio unit;

FIG. 4 is a bottom view of the audio unit;

FIG. 5 is a front elevation of the audio unit;

FIG. 6 is a rear elevation of the audio unit; and,

FIG. 7 is a side elevation of the audio unit.

The broken lines shown are included for the purpose of illustrating portions of the audio unit that form no part of the claim.
